UNITED STATES PATENT OFFICE

EARL C. BOOTH, OF INDIANAPOLIS, INDIANA, ASSIGNOR TO NOBLITT-SPARKS INDUSTRIES, INC., OF INDIANAPOLIS, INDIANA, A CORPORATION OF INDIANA

DESIGN FOR AN AUTOMOBILE BODY HEATER

Application filed July 24, 1931. Serial No. 40,673. Term of patent 7 years.

To all whom it may concern:

Be it known that I, EARL C. BOOTH, a citizen of the United States, residing at Indianapolis, in the county of Marion and State of Indiana, have invented a new, original, and ornamental Design for an Automobile-Body Heater, of which the following is a specification, reference being had to the accompanying drawings, forming part thereof.

Figs. 1 and 2 are front and side elevations

respectively of a heater embodying my new design.

I claim:

The ornamental design for an automobile-body heater, as shown.

In witness whereof, I have hereunto set my hand at Indianapolis, Indiana, this 22 day of July, A. D. one thousand nine hundred and thirty-one.

EARL C. BOOTH.
